UNITED STATES PATENT OFFICE.

LEE LINCOLN MANLEY, OF BROOKLYN, NEW YORK, ASSIGNOR TO RADIO CORPORATION OF AMERICA, A CORPORATION OF DELAWARE.

LOOP ANTENNA.

Application filed March 14, 1922. Serial No. 543,611.

The present invention relates to antennæ for receiving radio signals and more particularly to an improved arrangement for a loop antenna for small receiving sets such as are used by amateurs.

For receiving radio telegraphy and telephony loop antennæ are convenient especially where the use of overhead wires is objectionable or prohibited. In such cases it is usually desirable to have the loop antenna indoors, particularly when a portable receiving set is being used. The ordinary construction of loop antenna consists of a number of turns of wire mounted on a frame and is quite heavy and bulky and does not present a good appearance when used in a home or auditorium. It also cannot be readily set up, taken down or stored away as is desirable and therefore this has to a certain extent hindered the introduction in certain instances of apparatus for receiving radio telegraphy and telephony, such as broadcasting receivers.

The object of the invention is to provide a loop antenna construction which avoids the difficulties set forth and which is also inexpensive to manufacture.

In accordance with the invention, the turns of wire comprising the loop antenna are attached to a flexible sheet of material so that it may be rolled up in a convenient compact form. A loop antenna is directional and receives best when normal to the wave front of the waves to be received. To facilitate adjustment a support is provided at one end of the roll having a swivel or pivot so that the antenna may be rotated about a vertical axis.

In a particularly convenient embodiment of the invention the structure is mounted somewhat like a window shade and operated in a similar manner.

The novel features which I believe to be characteristic of my invention are particularly set forth in the appended claims, the invention itself, however, both as to its construction and mode of operation, together with further objects and advantages thereof, will best be understood by reference to the following description, taken in connection with the accompanying drawings in which:

Fig. 1 is a perspective view of a construction in accordance with the invention.

Figs. 2 and 3 are perspective views of modified supporting structures.

Figs. 4, 5 and 6 show a further modification.

In Fig. 1 the invention is illustrated in a manner in which it may be used in a window frame although it will be evident that it may be attached to a wall or other part of a building for example. The conductor 1 forming the loop may be a fine bare or insulated wire 1 sewed or otherwise attached to the sheet or fabric of a flexible curtain 2 which is adapted to be wound on a roller 3. One or more turns may be utilized as desired and these may be close together near the edge or wound in spiral shape of rectangular, circular or other contour. The terminals of the loop are brought out at any suitable points, for example, at the bottom of the sheet where they are attached to binding posts 4 and 5 fitted in the reinforcing strip 6. If desired one or more intermediate leads may be brought out from the intermediate turns and fastened to binding posts 8 to facilitate tuning.

An arm or bracket 9 for supporting the roller is hinged for rotation about a vertical axis, the hinge 10 being fastened to the window frame or wall in any appropriate manner. By this means the plane of the sheet may be turned through substantially 180° so that the plane of the loop may be adjusted to the optimum position for reception of signals from any direction. If desired, a catch may be utilized for holding the arm in the window frame or wall, but usually the friction of the hinge will be sufficient to maintain the arm in any position to which it is adapted. The roller may be attached to the arm to permit rotation in various ways, but a convenient construction as shown utilizes the usual spring roller to which a window shade is attached having pins 12, 13 fitting into arms 14, 15 attached to opposite ends of the bracket. As shown, one of the brackets 14 is slotted for receiving the flat or stationary pin 12 of the roller in order to facilitate removal. The rotating pin 13 is fitted in a circular hole. As the construction of the roller and its supports is well known, it will be unnecessary to par-

ticularly describe these details although it will be noted that the arms are both connected to the hinged bracket so that the roller may be swung around a vertical axis. When not in use the sheet is rolled up the same as an ordinary window shade. To put the antenna in service it is merely pulled down, connected to the receiving set and adjusted to any desired plane.

10 The construction of Fig. 2 is similar to Fig. 1 but has a roller bearing 16 such as used in casters, the plate 17 being attached to the top of the window frame or ceiling.

15 Fig. 3 shows a different type of hinge in which the pin 18 projecting from the window frame fits in a socket 19 attached to the rotatable arm. A catch such as the pin 20 and socket 21 is also provided for holding the lower end when the loop is pulled down so 20 that the sheet is held more or less fixed along one edge.

25 In some instances it may be convenient to eliminate the leads from the bottom of the shade and to provide permanent connections from the loop to the receiving set. This may be accomplished for example, by having the leads extend from the roller end instead of the other edges. This may be done in various ways, for example, with the ordinary shade 30 as shown in Figs. 4, 5 and 6. In Fig. 4 the ends of the loop are electrically connected to the usual metal caps 22, 23 at the end of the roller. The rotating pin 13 is riveted or otherwise fastened to the cap and the pin bearing 24 is insulated from the bracket. The binding post 25 which is insulated from the bracket is connected by a lead 26 to the insulated bearing. Another binding post 27 is electrically connected to the bracket. Electrical connection from the other end of the 40 loop to the binding post 27 will be made in the following manner using an ordinary shade roller. The metal cap 23 is electrically connected to the end of the loop. When the shade is not being drawn up or down the cap is electrically connected to the slotted bearing of the arm 14 through the rectangular tip 12 and the cam 28 forming a part thereof contacts with the dog 29 which is fastened by the pivot pin 30 to a disk of metal 31 fitting in the cap. This arrangement permits the antenna to be rolled up in the same manner as Fig. 1 and without the necessity of providing conspicuous leads to the detector.

55 Obviously the roller may be located at or near the floor and the free end drawn up in order to spread the loop.

60 Only 90° adjustment is required to place the loop normally to any wave front and therefore the vertical axis may be placed in a corner if desired instead of in a position where 180° rotation is permitted.

65 In the description the window shade types have been particularly described although all of the features thereof need not be utilized

and various modifications may be made without departing from the spirit of the invention.

Having described my invention, what I claim is:

70 1. A loop antenna construction comprising a coiled conductor and a support in the form of a sheet of flexible material having its surface disposed in an optimum plane for desired reception, said coil being mounted in the plane and within the marginal lines of said sheet.

75 2. A loop antenna construction comprising a coiled conductor consisting of a number of turns and a support for said conductor in the form of a sheet of flexible material having its surface disposed in an optimum plane for desired reception said conductor being mounted in the plane and within the marginal lines of said sheet and the turns being maintained 80 in spaced relation thereby.

85 3. An antenna construction comprising a support in the form of a sheet of flexible material adapted to be disposed in an optimum plane for desired reception, a wire like conductor mounted in the plane and within the marginal lines of the flexible material and a roller attached to said sheet and adapted to have said sheet and conductor wound thereon.

90 4. A loop antenna construction comprising a support in the form of a sheet of flexible material adapted to be disposed in an optimum plane for desired reception, a coiled conductor mounted in the plane and within the marginal lines of said sheet and a roller attached to said sheet and adapted to have said 95 sheet and conductor wound thereon.

100 5. A loop antenna construction comprising a support in the form of a sheet of flexible material adapted to be disposed in an optimum plane for desired reception, a coiled conductor mounted in the plane and within the marginal lines of said sheet and a roller attached to one edge of said sheet adapted to have said sheet and conductor wound thereon.

105 6. A loop antenna construction comprising an antenna support in the form of a sheet of flexible material adapted to be disposed in an optimum plane for desired reception, an antenna conductor mounted in the plane and within the marginal lines of said sheet, an arm attached to one edge of said sheet and a swivel at one end of the arm to permit rotation of the sheet and the conductor attached thereto.

110 7. A loop antenna construction comprising a support in the form of a sheet of flexible material adapted to be disposed in an optimum plane for desired reception, an antenna conductor mounted in the plane and within the marginal lines of said sheet, a roller attached to said sheet and adapted to have said sheet and conductor wound thereon and a swivel at one end of the roller for rotating the sheet and the conductor into different planes.

8. A loop antenna construction comprising a support in the form of a sheet of flexible material adapted to be disposed in an optimum plane for desired reception, a conductor mounted in the plane and within the marginal lines of said sheet, a roller attached to one edge of said sheet adapted to have said sheet and conductor wound thereon and a swivel for said roller having a vertical axis for rotating the sheet and conductor into different vertical planes. 60
9. A loop antenna construction comprising a support in the form of a sheet of flexible material adapted to be disposed in an optimum plane for desired reception, a coiled conductor mounted in the plane and within the marginal lines of said sheet, a roller attached to one edge of said sheet adapted to have said sheet and conductor wound thereon, a bracket for supporting said roller and a swivel connected to said bracket for rotating the sheet in different planes. 65
10. A loop antenna construction comprising a support in the form of a sheet of flexible material, adapted to be disposed in an optimum plane for desired reception, a conductor mounted in the plane and within the marginal lines of said sheet, a spring roller attached to one edge of said sheet, said sheet and conductor being adapted to be rolled on and off said roller under the action of the spring. 70
11. A loop antenna construction comprising a support in the form of a sheet of flexible material adapted to be disposed in an optimum plane for desired reception, a conductor mounted in the plane and within the marginal lines of said sheet, a spring roller attached to one edge of said sheet, said sheet and conductor being adapted to be rolled on and off said roller under the action of the spring and a support for said roller. 75
12. A loop antenna construction comprising a support in the form of a sheet of flexible material adapted to be disposed in an optimum plane for desired reception, a conductor mounted in the plane and within the marginal lines of said sheet, a spring roller attached to one edge of said sheet, said sheet and conductor being adapted to be rolled on and off said roller under the action of the spring, a support for said roller and a pivot for said support. 80
13. An antenna construction comprising a support in the form of a sheet of flexible material adapted to be disposed in an optimum plane for desired reception, a conductor mounted in the plane and within the marginal lines of said sheet, a spring roller attached to one edge of said sheet, said sheet and conductor being adapted to be rolled on and off of said roller under the action of the spring, a support for said roller and a pivot for said support located at one end thereof. 85
14. An antenna construction comprising a support in the form of a sheet of flexible material, adapted to be disposed in an optimum plane for desired reception, a conductor mounted in the plane and within the marginal lines of said sheet, a spring roller attached to one edge of said sheet, said sheet and conductor being adapted to be rolled on and off of said roller under the action of the spring, a support for said roller, and a pivot for said support, said pivot being disposed so that the sheet is rotatable into different vertical planes. 90
15. A loop antenna construction comprising a support in the form of a sheet of flexible material adapted to be disposed in an optimum plane for desired reception, a conductor mounted in the plane and within the marginal lines of said sheet, a roller attached to one edge of said sheet, a pivot for said roller and leads connected to the end of said coiled conductor extending to terminals attached to the edge of said sheet which is located on the edge opposite that which is attached to the roller. 95
16. An antenna comprising a support in the form of a flat sheet of flexible fabric, and an antenna conductor secured to said sheet and conformed to provide a plurality of turns which are maintained in spaced relation and in substantially the same plane by said fabric, said fabric with the conductor secured thereto being adapted to be folded or rolled into a compact parcel. 100
17. An antenna comprising a rectangular sheet of textile fabric and a conductor comprising a plurality of turns which are secured to said sheet and which lie in the same plane when the said sheet of textile fabric is held taut in a vertical plane, and means at the lower edge of the sheet for holding the latter substantially taut in a vertical plane when the antenna is supported and oriented by grasping the said sheet at its upper corners. 105
